[57] CLAIM

The ornamental design for an industrial fuel burner, substantially as shown and described.

DESCRIPTION

FIG. 1 is a rear perspective view of an industrial fuel burner showing my new design;

FIG. 2 is a rear elevational view thereof;

FIG. 3 is a front elevational view thereof;

FIG. 4 is a top plan view thereof;

FIG. 5 is a right side elevational view thereof;

FIG. 6 is a left side elevational view thereof;

FIG. 7 is a bottom plan view thereof.

The dotted lines shown in the several views are disclosed for illustrative purposes only.

FIG. 1

FIG. 2

FIG. 3

FIG. 4

FIG. 5

FIG. 6

FIG. 7
